UNITED STATES PATENT OFFICE.

CHARLES T. SCHOEN, OF PHILADELPHIA, PENNSYLVANIA.

BOLSTER GUIDE-BAR FOR CAR-TRUCKS.

SPECIFICATION forming part of Letters Patent No. 437,722, dated October 7, 1890.

Application filed January 24, 1890. Serial No. 337,980. (No model.)

To all whom it may concern:

Be it known that I, CHARLES T. SCHOEN, a citizen of the United States, residing at Philadelphia, in the county of Philadelphia and State of Pennsylvania, have invented a certain new and useful Improvement in Bolster Guide-Bars and Bolster-Guide-Bar Plates, of which the following is a full, clear, and exact description.

10 The object of this invention is to produce, from pressed steel especially, a bolster guide-bar and a bolster-guide-bar plate for railway-car trucks.

15 The invention consists of a bolster guide-bar and a bolster-guide-bar plate constructed, by preference, of pressed steel, substantially in the manner hereinafter more particularly set forth and finally claimed.

20 In the accompanying drawings, illustrating my invention, in the several figures of which like parts are similarly designated, Figure 1 is a front elevation, Fig. 2 a side elevation, Fig. 3 a top plan view, Fig. 4 a bottom plan view, and Fig. 5 a cross-section taken in the 25 plane of line $x x$, Fig. 1, of the bolster guide-bar. Fig. 6 is an elevation, and Fig. 7 a longitudinal section, of the bolster-guide-bar plate; and Fig. 8 is a perspective view of portions of a railway-car truck in outline with 30 my guide-bar and plate applied. Fig. 9 is a perspective view of a modified form of guide-bar.

35 The bolster guide-bar a is struck up in dies or by other suitable devices and from sheet or plate steel or other wrought metal which may be found in open market, or may be made in shape to order. In order to obtain the requisite strength, this guide-bar is bellied centrally, as at b , and, preferably, in the arcs 40 of circles, as indicated in the sectional view, Fig. 5. The ends c may be squared and turned in to form heads, as at d and e , and these heads are provided with openings f and g , respectively, for the passage of a through-bolt h , (shown in dotted lines in Fig. 8,) for connecting the parts with the braces or beams of the truck. Side wings i are provided for co-operation with the bolster guide-plates. (Shown in Figs. 6, 7, and 8, and hereinafter 45 more particularly described.) The wings i are enlarged at their lower ends to form flanges j , which are provided with bolt-holes to receive the bolts k , (see Fig. 8,) by means of which the bolster guide-bar is secured to the truck.

50 The bolster-guide-bar plate l (see Figs. 6,

7, and 8) has struck up the parallel ribs m , which form ways to receive the wings i of the bolster guide-bar and to guide the parts in the movement of the truck. Holes n are made in the guide-bar plate for the reception of 6c fastening devices to secure the guide-bar plate to the truck.

The parts are assembled as clearly indicated in Fig. 8. Very obviously modifications in the form of these parts will be made 65 to suit the requirements of railway construction, and these I esteem as within my invention so far as they contain the principle of my invention.

These wrought-metal bolster guide-bars and 70 bolster-guide-bar plates will be constructed so that they may be interchangeable with the cast-metal and other bolster guide-bars and guide-bar plates in common use, so that in repairing cars old bolts and old bolt-holes may 75 be employed in assembling my improved bars and plates. Another and manifest advantage of my invention is the great difference in weight in favor of my construction without any impairment of strength or durability, but rather in gain of both.

In the use of the term "bellied," as applied to the longitudinal elevation of the bolster guide-bar, I mean to include any form or extent of elevation of the metal which will 85 strengthen the guide-bar. For example, the bellying may be angular, as indicated in Fig. 9, instead of curvilinear, and it may be in a single straight line instead of at inclinations.

What I claim is—

1. A pressed-steel or other wrought-metal bolster guide-bar having edge flanges for attachment to a part of the truck, bellied longitudinally and having terminal heads for the reception of the connecting-bolt, and also 95 having wings for co-operation with a bolster-guide-bar plate, substantially as and for the purpose described.

2. A bolster guide-bar provided with base-flanges, wings, and an intermediate bellied 100 portion of curvilinear outline and terminating in squared end portions or heads and constructed of pressed steel or other wrought metal, substantially as described.

In testimony whereof I have hereunto set 105 my hand this 23d day of January, A. D. 1890.

CHARLES T. SCHOEN.

Witnesses:
